[57] **CLAIM**

The ornamental design for a mirrored medicine cabinet with light bridge, as shown and described.

DESCRIPTION

FIG. 1 is a top, front, and left side perspective view of a mirrored medicine cabinet with light bridge showing my new design;

FIG. 2 is a front elevational view thereof;

FIG. 3 is right side elevational view thereof;

FIG. 4 is a top plan view thereof;

FIG. 5 is a bottom plan view thereof;

FIGS. 6 and 7 are enlarged fragmentary cross-sectional views thereof, showing portions of the cabinet taken along lines 6—6 and 7—7 of FIG. 2, respectively, to better illustrate the contours thereof;

FIG. 8 is an enlarged, fragmentary front elevational view of FIG. 2, to better illustrate the contours thereof; and,

FIG. 9 is a cross-sectional view of FIG. 8, taken along lines 9—9 to better illustrate the contour thereof.

The undisclosed rear of the cabinet is unadorned and is not seen when the cabinet is in place.
